UNITED STATES PATENT OFFICE.

WILLIAM EVERETT VER PLANCK, OF ERIE, PENNSYLVANIA, ASSIGNOR TO GENERAL ELECTRIC COMPANY, A CORPORATION OF NEW YORK.

VALVE MECHANISM FOR INTERNAL-COMBUSTION ENGINES.

4,196,497.

Specification of Letters Patent. Patented Aug. 29, 1916.

Application filed February 26, 1914. Serial No. 821,383.

To all whom it may concern:

Be it known that I, WILLIAM EVERETT VER PLANCK, a citizen of the United States, residing at Erie, county of Erie, State of Pennsylvania, have invented certain new and useful Improvements in Valve Mechanisms for Internal-Combustion Engines, of which the following is a specification.

The present invention relates to valve mechanism for internal combustion engines, and more especially to those of the opposed piston type operating on the high compression cycle and having compressed air starting means.

15 Briefly stated, my improvement comprises a novel arrangement of parts whereby the air starting valve, fuel valve, and fuel pump are actuated by a connecting rod of the engine thereby avoiding the use of a cam shaft and its associated parts. This means a material saving in the number of parts and results in a simpler and less expensive engine. Further the air starting valve, fuel valve and fuel pump are so arranged as to be under 20 the control of a single operating handle or lever.

25 My improvements are directed chiefly to engines intended to drive motor cars which are of the variable speed type and will be described with this in view, but my invention is not necessarily limited thereto.

30 The principal advantageous features of my invention reside in the fact that the cam shaft is done away with and a single lever located at any convenient point enables the operator to start or stop the engine; to vary the amount of fuel delivered by the pump to the fuel injectors over the full range of load; to vary the point of opening of the fuel valve 35 for different loads; to shut off the effective delivery of the pump during the air starting period, thereby avoiding the use of auxiliary devices to relieve the fuel pump pressure; and to move the starting valve actuator 40 quickly into and out of operative relation with respect to the connecting rod.

45 In the accompanying drawings which illustrate one of the embodiments of my invention, Figure 1 is a view in side elevation, with certain of the parts broken away, of a heavy oil engine illustrating one of the embodiments of my invention; Fig. 2 is a detailed view on a larger scale showing the means for operating the valves from one of the side rods; Fig. 3 is a sectional view of a

part of the controlling mechanism, and Fig. 4 shows a hand lever controlling the engine as a whole.

The engine shown is of the multi-cylinder type, although my invention can be also applied to an engine having a single cylinder. Furthermore, my invention is shown in connection with an engine having oppositely moving pistons in the same cylinder, and while my invention is particularly adapted for an engine of this character it is not limited thereto in all particulars, as will be evident from a study hereof.

50 5 indicates a cylinder containing a lower piston 6 and an upper piston 7. The lower piston is connected to the main shaft 8 by a connecting rod in the usual manner and the upper piston is connected to the main shaft by a pair of side connecting rods 9, only one of which is shown, the other being on the 55 farther side of the cylinder. The upper ends of these rods are connected to a cross-head 10, the latter moving in guides 11. The exhaust gases leave the cylinder by the conduits 12 of which two are provided. Fuel 60 is admitted to the engine under the control of a needle valve 13, shown in dotted lines, the latter being located in an injector of any suitable or well-known construction. As a general thing the fuel will be injected into 65 the cylinder by means of a body of highly compressed air, generally referred to as the blast air.

70 The needle valve is raised from its seat against the pressure of a spring or compressed air by the lever 14, the latter being mounted on a spindle 15. Mounted on the spindle is a second lever 16 carrying a roller at its free end. In order to actuate the fuel valve at the proper time two movable and co-operating members 17 and 18 are provided which are pivotally united by the pin 19. One end of the member 17 is pivotally supported by an eccentric 20 located on the control shaft 21. The lower end of 75 the member 18 is connected to a connecting rod, as, for example, to the side rod 9 by the pin 22 which has an orbital path as indicated by the broken and dotted lines 23, Fig. 2. Carried by the member 18 and subjected to the modifying influence of one member on the other is a cam 24 which may be adjusted longitudinally as by means of the nut and screw 25. As the connecting rod swings to and fro the cam 24 will be 80 85 90 95 100 105 110

given an orbital movement and cause the lever 16 to open the needle valve once for each revolution of the crank shaft. Owing to the fact that the fulcrum for the lever members 17 and 18 is made in the form of an eccentric as it is turned in one direction or the other it will change the timing of the fuel valve. That is to say the cam 24 will engage the roller on the fuel valve lever 16 earlier or later and hence a greater or less amount of fuel will be admitted to the combustion chamber. I also drive the fuel pump from the connecting rod by the same means that are employed to actuate the fuel valve. To this end a lever 30 is provided through which the pivot 19 passes. The upper end of the lever is connected to the member 17 by pin 31, and the latter is held in position by the spring 32 which enters the slot therein. The lower end of the lever is connected to a walking beam 33, the left-hand end of which is connected by a link 34 with the cross-head carrying the pump plunger 35. This pump is provided with a suction valve 36, whose stem projects below the pump casing and is controlled by the action of the arm 37. The arm 37 vibrates in synchronism with the plunger due to the connecting rod or link 38 and by moving the point of connection between the rod 38 and the arm 37 toward or away from the fulcrum of said arm. The time of closing of the suction valve will be earlier or later as the case may be, thus regulating the engine by causing a greater or less amount of oil to be delivered by the pump to the fuel injector. The position of the rod 38 may be changed by a system of levers 39 and link 40 through the control shaft 21 and controlling handle 41, Fig. 3. In order to insure the filling of the pipe leading to the fuel injector prior to starting, the pivot pin 31 is removed which disconnects the lever 30 from the members 17 and 18 and thereafter the pump plunger can be reciprocated by the hand lever 33. After a few strokes the pivot pin is restored to place and the engine is ready for starting. I do not claim herein the specific construction of this pump since it forms the subject matter of my Patent No. 1,116,959 dated November 10, 1914.

The engine herein illustrated depends for its operation on compressing the air in the working cylinder to a temperature above the igniting temperature of the fuel. This, therefore, means high compression pressure and some sort of a starting means. In the present instance the engine is started by compressed air subject to the control of the starting valve 43, shown in dotted lines, which is actuated by a connecting rod, as for example, by the side rod 9 at the proper time through the following means: 44 indicates a lever for opening the valve and 45

a second lever for moving the first, both being secured on the spindle 46. 47 indicates a cam lever which is mounted on the eccentric 48, the latter serving as a fulcrum therefor. The eccentric is mounted on the control shaft 21, Fig. 3. The upper end of the cam lever is connected by the link 49 to the lever 45. The lower end of said lever 47 is provided with a cam 50 which, when the eccentric 48 is turned to a predetermined position by the hand lever 41, is moved into co-operative relation to the roller 51 which is mounted on the connecting rod, said roller having an orbital movement as indicated in broken-and-dotted lines in Fig. 2. When the engine is operating on fuel the roller 51 has no effect on the lever 47 nor on the starting valve 43 and hence said parts remain stationary.

In an engine of this character, it is important to reduce the number of controlling devices to the minimum to avoid mistakes in operating and to simplify the apparatus as a whole. I have so arranged the apparatus heretofore referred to that it can be controlled by a single handle or lever, such as 41, forming a selective controlling device. The travel of the hand lever is indicated in Fig. 4. Moving the lever from the neutral to a vertical position causes the fuel admitted to the engine to vary from minimum to maximum. In moving from the position marked "Neutral" to that marked "Air start" air is caused to be admitted to one or more of the working cylinders where it drives the engine as an air motor. During the starting period it is important to shut off the supply of fuel to the injector since otherwise there would be an undue accumulation of fuel in the injector, giving rise to excessive pressures and possibly causing damage on the first firing stroke. In order to prevent the pump from delivering fuel and at the same time throw the starting mechanism into operation the two eccentrics 20 and 48, Fig. 3, are provided and mounted on the control shaft 21. The eccentrics are oppositely disposed, as shown in Fig. 3, and are so arranged that a considerable angular movement of the shaft 21 and the hand lever 41 will not materially change the relation of the parts. Furthermore, the parts are so related that as the hand lever 41 is moved from the neutral to the full load position the cam 50 is progressively moved out of the path of the roller 51. As will be evident, the main thing is to keep the cam 50 and roller 51 from engaging except during the starting period. When the handle 41 is swung to the left, Fig. 4, it first shuts off the fuel supply by moving the arm 37 to a point where it prevents the suction valve of the pump from seating and, therefore, the fuel instead of being delivered to the injector will be merely sucked into the pump 125

cylinder and then discharged. Continued movement of the handle in the same direction turns the eccentrics 20 and 48 by such an amount as to lower the cam 24 and get it out of the path of the roller on lever 16 and raise the cam lever 47 until the cam 50 is engaged by the roller 51 each time it makes a complete orbital movement. Under these conditions air is admitted by a pipe 52 from a suitable supply tank under the control of a hand valve. Assuming that the engine stopped in proper position it will start when air is thus admitted. If it did not stop in the proper position it will be necessary to bar the shaft around to starting position. The engagement of the cam 50 and roller 51 causes the lever 44 to open the air starting valve 43 and high pressure air entering between the pistons 6 and 7 starts them into operation as an air motor. This action is continued until the engine is well under way when the starting lever 41 is pushed back across the neutral position which lowers the cam lever 47 and the cam 50 and raises the cam 24 into position where it will actuate the fuel valve each time the fulcrum pin 22 completes an orbital movement. I prefer to use one of the side connecting rods for actuating the valves because it is more accessible but the invention is not necessarily limited thereto.

In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. In an internal combustion engine, the combination of a working cylinder and piston, a crank shaft, a connecting rod between the piston and shaft, a fuel valve, a starting valve, mechanism actuated directly by the connecting rod for operating the valves, and a selective controlling device for causing said mechanism to actuate the fuel valve or the starting valve.

2. In an internal combustion engine, the combination of a working cylinder and piston, a crank shaft, a connecting rod between the piston and shaft, a fuel valve, a starting valve, a means actuated directly by the connecting rod for operating the fuel valve, a means actuated by the connecting rod for operating the starting valve, and a device for moving one of said means into action and at the same time moving the other means out of action.

3. In an internal combustion engine, the combination of a working cylinder and piston, a crank shaft, a connecting rod between

the piston and shaft, a fuel valve, a starting valve, a pump capable of supplying variable amounts of fuel to the valve and cylinder, mechanism actuated by the connecting rod for operating the fuel valve and the starting valve, and a device which controls the pump and also determines whether the connecting rod shall move the fuel valve or the starting valve.

4. In an internal combustion engine, the combination of a working cylinder and piston, a crank shaft, a connecting rod between the piston and shaft, a fuel valve, a pump for supplying fuel to the valve and cylinder, a regulator for the pump, a starting valve, mechanism actuated by the connecting rod for operating the fuel valve, pump regulator and starting valve, and a device for controlling the action of the mechanism on the fuel valve, pump regulator and starting valve.

5. In an internal combustion engine, the combination of a working cylinder and piston, a crank shaft, a connecting rod between the piston and shaft, a fuel valve, a pump supplying fuel to the valve, a regulator for the pump, a starting valve, a system of levers that is constantly vibrated by the connecting rod for actuating the fuel valve, pump and starting valve, and a means acting on said system of levers and the pump regulator to cut the pump and fuel valve out of service and the starting valve into service for starting purposes.

6. In an internal combustion engine, the combination of a working cylinder and piston, a crank shaft, a connecting rod between the piston and shaft, a fuel valve, a pump supplying fuel to the valve, a starting valve, a system of levers that is connected directly to and vibrated by the connecting rod for normally actuating the fuel valve, and a means for modifying the relation of the levers one to another to stop their action on the fuel valve and move them into position to actuate the starting valve.

7. An internal combustion engine comprising a working cylinder and piston, a crank shaft, a connecting rod between the piston and shaft, a fuel valve, a fuel pump, and an air starting valve, in combination with a set of levers arranged to actuate the fuel valve and pump during the normal operation of the engine, a second set of levers for actuating the starting valve, both of said sets being vibrated by the connecting rod, a fulcrum common to the sets of levers, and a means for adjusting said fulcrum to move one set of levers into operation and the other set out of operation.

8. An internal combustion engine comprising a working cylinder and piston, a crank shaft, a connecting rod between the piston and shaft, a fuel valve, a fuel pump, and an air starting valve, in combination

- with a pair of connected levers for actuating the fuel valve, one of said levers being pivotally connected to the connecting rod, a fulcrum for the other lever supported by the engine, a cam lever and connected arm for actuating the starting valve, said cam lever being supported by the fulcrum, a means moved by the pair of connected levers for actuating the pump plunger, a regulator for the pump, and a means for adjusting the position of the fulcrum to put the starting valve into operation and the fuel valve out of operation and adjusting the regulator of the pump to render the pump inoperative.
9. An internal combustion engine comprising a working cylinder and piston, a crank shaft, a connecting rod between the piston and shaft, a fuel valve, a fuel pump, and an air starting valve, in combination with connected levers vibrated in synchronism with the crank shaft to actuate the fuel valve and the pump, a cam lever and means for actuating the starting valve, a fulcrum that is common to said connected levers and cam lever, a regulator for the pump, a means for transmitting motion from the fulcrum to the regulator, and means for adjusting the fulcrum to put the fuel valve out of operation and the starting valve and cam lever into operation and adjust the regulator to stop the effective delivery of the pump.
10. An internal combustion engine comprising a working cylinder and piston, a crank shaft, a connecting rod between the piston and shaft, a fuel valve, a fuel pump, and an air starting valve, in combination with connected levers vibrated in synchronism with the crank shaft to actuate the fuel valve and the pump, a cam lever and means for actuating the starting valve, eccentrics that form fulcrs for the connected levers and cam lever, a control shaft for supporting the fulcrs, a pump regulator, a connection between the control shaft and the regulator, and a handle arranged to

move the shaft to a given angular position to put the air starting valve into operation and move the regulator to stop the pump, and to different angular positions to put the fuel valve and pump into operation and adjust the regulator to vary the pump delivery.

11. In an internal combustion engine, the combination of a working piston and cylinder, a crank shaft, a connecting rod connecting the piston and shaft, a fuel valve, a pair of pivotally united levers for actuating the fuel valve, one of said levers being connected to the rod, the other having a fulcrum carried by the engine, a starting valve, a cam lever and means for actuating the starting valve, the lever being mounted on said fulcrum, a means on the connecting rod and normally inactive for moving the cam lever, and means for adjusting the fulcrum to a position where the pair of levers are inoperative as regards the fuel valve, and the cam lever is moved into the path of its actuating means on the connecting rod.

12. An internal combustion engine comprising a piston and cylinder, a crank shaft, a fuel pump, a fuel valve, and an air starting valve, in combination with a lever system for actuating the pump and fuel valve, a connecting rod between the shaft and piston which is pivotally connected to the lever system for vibrating it, a cam lever and means for actuating the starting valve, said lever being normally idle, a means carried by the connecting rod and projecting into the path of the cam lever, and a device for rendering the lever system inactive as regards the fuel valve, and for moving the cam lever into position to be engaged by the means on the connecting rod.

In witness whereof, I have hereunto set my hand this 20th day of February, 1914.

WILLIAM EVERETT VER PLANCK.
